Patented July 1, 1919.

UNITED STATES PATENT OFFICE.

CHARLES G. BAUER, OF BROOKLYN, NEW YORK.

COMPOUND AIR-PUMP.

1,308,387.

Specification of Letters Patent.

Patented July 1, 1919.

Application filed June 1, 1917. Serial No. 172,177.

To all whom it may concern:

Be it known that I, CHARLES G. BAUER, a citizen of the United States, residing at Brooklyn, in the county of Kings and State 5 of New York, have invented certain new and useful Improvements in Compound Air-Pumps; and I do hereby declare the following to be a full, clear, and exact description of the invention, such as will enable others 10 skilled in the art to which it appertains to make and use the same.

My present invention relates to an improvement in compound air pumps such as are used for inflating pneumatic tires and 15 the like, and provides a cheap and simple construction whereby the base is made far more durable than heretofore as well as lighter and more sightly.

In pumps of this kind as heretofore made, 20 the bottoms of the high and low pressure cylinders have been screwed from above into appropriate openings in a heavy cast iron base, and it has been necessary to bore slanting openings for passage of air through the 25 material separating the two chambers in the base which receive the cylinders. These bases, besides being more or less unsightly, are quite heavy, and are easily broken when the pump is dropped or is accidentally 30 struck. They are also likely to leak if great care is not exercised in assembling.

It has long been deemed desirable to provide some construction suited to the use of sheet metal, preferably steel, in the making 35 of these bases. It is evident that this material offers the advantage of superior lightness, takes up less room and is practically unbreakable. My invention covers a structure which solves this problem in a practi- 40 cal manner and with economy of labor and material.

My improved pump also comprises cer- 45 tain novel features in connection with the finishing of the upper end of the high pressure cylinder which are hereinafter described.

My improved pump is illustrated in a pre- 50 ferred form in the accompanying drawings, wherein Figure 1 is an elevation of the pump with parts shown in vertical section, Fig. 2 is a bottom plan view of the same, and Fig. 3 is a horizontal sectional view showing the tops of the cylinders in plan.

The usual high and low pressure cylinders 55 used in pumps of this kind are shown at 10 and 11, respectively, and the two piston rods

12 and 13 are joined at their tops by the usual common handle 14.

My improved base, for joining the cylinders 10 and 11 is composed of two sheet metal plates, preferably of steel, each of 60 which is stamped into form, before they are joined. The first of these is shown at 15. It has a down-turned edge 16, and is preferably furnished with a depression 17 to receive the second plate which is made to fit said de- 65 pression. The upper surface of this first or main plate is formed with two upwardly ex- tending cylindrical portions 18 and 19.

The second, or closing plate, is shown at 20, and is made to fit the depression 17 in 70 the preferred form, although it is not, of course, essential to the invention that any depression should be provided in this connection. This plate 20 is also provided with a recessed part 21, stamped into appropriate 75 form in a well known manner.

In assembling the pump, the straight plain tubes 10 and 11 designed to act as cylinders are passed up through the cylindrical portions 18 and 19, until the slightly flar- 80 ing lower ends of said tubes fit snugly against the interior surfaces of said openings. The tubes are then securely joined to the plate 15 in this position by the "sweating" process, thus providing a very strong joint, 85 and one that is entirely and permanently air tight. The second or closing plate 20 is then fitted to its seat and is sweated in place. In this position the depression or recess 21 affords ample room for free passage of air 90 from one cylinder to the other.

The closing device for the top or discharge end of the high pressure cylinder comprises three principal portions.

First, the under part of the sheet metal cap, 95 shown at 22, is formed below to screw onto the top of the pipe 10 and is extended on one side, as shown in Figs. 1 and 3, to accommodate a suitable opening to receive the usual valve 23 on the end of the flexible 100 air-delivery pipe 24. The upper surface of this under portion is spun outward to form a horizontal flange 25.

The upper part of the sheet metal cap is shown at 26, and is provided with a peripheral portion having an upper face 27, which is turned at its edge first downward and then inward to fit snugly under the flange 25 on the lower cap. Between the portion 27 of the upper cap and the flange 25 of the 110

lower cap is inserted a flat packing 28, which may be of rubber, fiber, paper or wicking. The whole is strongly compressed in manufacture, and provides a strong and permanently air tight closure.

- Over the center of the tube 10, the upper cap is stamped or spun downward to form a packing cup 29, into which is screwed a closing gland 30 having a polygonal head as shown in Fig. 3 to permit use of a tool in screwing it home. The usual packing is placed beneath the gland, and there is thereby formed an air tight packing for the piston rod 12.
- In order firmly to unite the two cylinders 10 and 11 at their upper ends, the air tight cap 31 on the cylinder 11 is furnished with an ear 32 of sheet metal which extends over the top of the cap portion 26, and is provided with an opening through which passes the gland 30. The ear 32 is thus secured under the flange at the top of the gland.

It will be seen that my improved non-breakable base is so constructed as to afford ample room for passage of air from one cylinder to the other, while taking up much less room than the old cast iron base, and affording a more reliable and durable air-tight construction.

What I claim is—

30
In a pump of the class described, a closing cap for the high pressure cylinder comprising a lower portion fitting said cylinder and having an extension for receiving the valved end of the delivery pipe, said portion having 35 a horizontal flange supporting a packing; in combination with an upper portion provided with a packing gland and having its periphery turned first downward and then inward and compressed under the flange and 40 packing of the lower cap portion.

In testimony whereof, I affix my signature.

CHARLES G. BAUER.
